UNITED STATES PATENT OFFICE.

JOHAN M. ANDERSEN, OF BOSTON, MASSACHUSETTS, ASSIGNOR TO ALBERT AND J. M. ANDERSEN MANUFACTURING COMPANY, OF BOSTON, MASSACHUSETTS, A CORPORATION OF MAINE.

OIL-SWITCH.

1,094,693.

Specification of Letters Patent. Patented Apr. 28, 1914.

Application filed July 23, 1908. Serial No. 444,977.

To all whom it may concern:

Be it known that I, JOHAN M. ANDERSEN, a citizen of the United States, residing in Boston, county of Suffolk, and State of Massachusetts, have invented an Improvement in Oil-Switches, of which the following description, in connection with the accompanying drawings, is a specification, like letters on the drawings representing like parts.

10 This invention relates to electric circuit controllers especially designed and adapted among other uses to be employed on circuits carrying currents of high potential.

The present invention has for its object 15 to provide a switch or circuit controller, which is simple and efficient in operation and with which the danger of shocks to the operator is eliminated or at least reduced to a minimum, as will be described.

20 These and other features of this invention will be pointed out in the claims at the end of this specification.

Figure 1 is a perspective of a switch or circuit controller embodying this invention. 25 Fig. 2, a similar view with the oil well or receptacle removed. Fig. 3, a view like Fig. 2, but more in perspective with the switch in its open position. Fig. 4, a detail in plan to be referred to. Fig. 5, an enlarged detail in vertical section and elevation to be referred to, the section being taken on the line 5—5, Fig. 7. Fig. 6, a detail of one of the locking bars for the oil well, and Fig. 7, a partial transverse section and end elevation to be referred to.

30 In the present instance, the invention is shown as embodied in a three pole double break switch, having three movable members *a*, *b*, *c*, which coöperate with three sets of pairs of stationary members as will be described. 35 Each movable member may be made as herein shown and consists of a contact member 10 composed of a plurality of laminations or brushes, which are secured 40 between the two parts 12, 13 of a holder, by means of a screw 14 (see Fig. 5).

The part 13 of the holder is provided with upright lugs or ears 15, which straddle or embrace the lower edge of a carrier 16 for 45 the movable members *a*, *b*, *c*, and are secured thereto by a screw or bolt 17. The carrier 16 may be made as a plate or slab of slate or other insulating material and is common to all the movable members of the switch.

50 The part 12 of the holder is made substan-

tially the length of the laminations of the movable contact member 10 to firmly support the same, and is provided at its opposite ends with arms 18, to the opposite sides of which are secured yielding fingers 19 55 having contact pieces 20 secured to their upper ends, and forming auxiliary contacts, as will be described. Each end of the laminated contact member 10 coöperates with a fixed contact member, preferably of the construction herein shown and consisting of a flat metal plate or block 21 having extended from its upper surface clamping lugs 22, which are suitably grooved on their adjacent surfaces to form a socket for the reception 60 of the lower end of a metal rod 23, with which the lugs are firmly engaged by the clamping screws 25, (see Fig. 7). This construction of the stationary contact member enables the latter to be quickly and easily 65 adjusted on its supporting rod 23, so as to obtain an even or uniform contact between the stationary contact members 21 and the laminated movable members 10. The supporting rod 23 is insulated from a metallic 70 frame constituting the main support for the switch, and comprising as herein shown a metal plate or platform 26 provided with side flanges 27 and extended from a metal upright 28, said plate having suitable holes 75 or openings for the passage of the rods 23 above and below the same.

One of the features of this invention consists in a novel insulator for electrically separating the contact supporting rod 23 from the metal plate or frame 26, and for permitting the terminal which coöperates with the line cable or conductor 29 to be soldered thereto before said terminal is fastened to the rod 23. For this purpose the insulator is 90 composed as herein shown of three members or sections 30, 31 and 32 (Figs. 5 and 7), the section 30 being located below the frame or metal plate 26 and comprising a sleeve having a depending flange 34 at its lower end, 95 and an enlarged socket 35 at its upper end, into which extends the portion of the sleeve 31, which projects through the hole in the frame 26. The section 31 is provided at its upper end above the frame 26 with an annular flange or lip 36, forming a socket 37 into which extends the reduced lower end 38 of the section 32, which is provided with a shoulder 39 resting upon the flange 36 (see Figs. 5 and 7).

110

The sections 30, 31, are firmly clamped to the metal frame 26 above and below the same by the rod 23, which is provided near its upper end with a flange or collar 40 resting upon the upper edge of the sleeve 31, and a nut 41, which engages the lower side or end of the sleeve 30. The upper section 32 rests loosely upon the flange or lip 36 of the intermediate section 31 and is free to be moved along the cable or conductor 29, so as to permit a terminal piece 42 for the cable or conductor 29 to be soldered to the cable and practically form part thereof and allow the terminal to be made so as to be clamped to the upper end of the rod 23. The terminal piece 42 is preferably made as herein shown and is provided at its upper end with a socket 43 for the reception of the end of the cable or conductor 29, and is provided at its lower end with a split socket 44 for the reception of the upper end of the rod 23, said split socket having lugs or ears 45 for the passage of screws or bolts 46, by turning up which the split socket can be contracted so as to firmly grip or engage the rod 23 and obtain a good electrical connection between the cable 29 and the said rod. The sections 32 of the insulator are made longer than the terminal piece 42, so as to thoroughly protect the operator from contact with the same.

The movable members of the switch are secured as described to a plate or slab of slate, wood or other insulating material, which is located below the platform 26 of the supporting frame and is connected to an operating mechanism to be described, which is located above the said platform. The operating mechanism referred to, consists as herein shown of a substantially horizontal lever 50 pivoted at 51 to the upright portion 28 of the supporting frame, and having its free end joined by a link 52 (see Fig. 5) to a metal rod 53, which is provided with a screw-threaded lower end 54 to engage a threaded socket in a metal rod or nut 55 fitted into a hole extended through the plate or carrier 16 for the movable members of the switch and intersecting a vertical hole in the top edge of the plate through which the threaded end 54 is passed (see Fig. 5), the metal rod 53 being extended through a suitable hole in the platform 26 and having thereon a sleeve 56 of insulating material located below a flange 57 on said rod. The lever 50 has joined to it intermediate its ends a vertically arranged link or lever 59 forming one member of a toggle, the other member 60 of which is pivoted at 61 to the bottom of the upright portion of the frame. The toggle levers 59, 60 are operated by a link 62 provided at its inner end with a slot 63 for a purpose as will be described, and through which the center pivot or pin 64 for the toggle levers is extended, said link being

extended through the upright portion 28 of the supporting frame, through an upright post or wall 66 to which the supporting frame is secured, and through a plate or casting 67 secured to the front side of the post or wall 66. The end of the link 62 at the front side of the post or wall 66 is pivotally secured to a lever 69, which is pivoted at its lower end to a lug or projection 70 on the plate or casting 67. The lever 69 when turned into a substantially vertical position shown in Figs. 1 and 2 moves the link 62 in a substantially horizontal path and causes the inner end of the slot 63 to engage the pin 64 and move the toggle levers 59, 60 into their straightened position shown in Fig. 5. This movement of the toggle turns the lever 50 on its pivot so as to elevate its free end and thereby, through the link 52 and rod 53 lift the plate or carrier 16 and the movable contact members attached thereto, up into the position shown in Figs. 2 and 5, in which position, the main movable contact members or spring brushes 10 are engaged with the flat underside of the stationary contact members or plates 21, while the auxiliary movable contact members 20 are engaged with opposite sides of the plates or stationary contact members 21, thus closing the switch or circuit controller.

Provision is made for locking the switch in its closed position just described, which may be accomplished by a locking device, herein shown as a latch or hooked lever 74, pivoted between lugs 75 on the plate 67 and adapted to engage the operating lever 69, when the latter is moved into its closed position shown in Figs. 1 and 2, and provision is made for releasing said lever, which may be accomplished by a sliding rod or plunger 76 movable in the handle 77 of the lever 69, said handle being made hollow to permit the rod 76 to extend through the same, so as to be capable of engaging the free end of the latch 74 and depress it against the action of a spring (not shown), which normally holds the latch up into engagement with the lever 69. The releasing rod 76 extends above the handle and can be depressed to engage the latch 74 by the thumb of the operator, and said rod may be restored to its normal or projecting position shown in Fig. 1 by a spring located in the hollow handle and not herein shown. After the latch 74 has been depressed, the operator moves the lever 69 back into the position shown in Fig. 3, which causes the link 62 to move the length of the slot 63 before it engages the center pin 64 of the toggle and without moving the contact member 10, after which the link moves the toggles into an inclined position, thereby permitting the carrier 16 and the movable contact members attached to it to drop by gravity with a sudden or quick

motion and disengage the main contact brushes 10 and then the auxiliary contacts 20 from the stationary contact members 21, and consequently effect a quick opening of the switch or circuit controller. The quick and accelerating downward movement of the movable contact members and their carrier is permitted by the loose or slotted connection between the link 62 and the center 10 pin 64 of the toggle, the slot 63 permitting the carrier 16 and movable contact members to move downwardly independently of the movement of the link 62 and the operating lever 69, and this movement may be hastened by increasing the weight of the slab or carrier 16 to overcome the friction. When it is desired to close the switch, the operator moves the lever 69 from its substantially horizontal position shown in Fig. 20 3, to the substantially vertical position shown in Figs. 1 and 2.

The switch above described is especially adapted for use in high tension circuits, and provision is made for opening and closing the switch in oil or like non-conducting fluid. For this purpose, the supporting frame for the switch has detachably secured to it an oil well, comprising a metal box or vessel 80 open at its top for the reception of the parts 30 of the switch located below the platform 26, said box being provided with a lining 81 of wood or other non-metallic material and with an inner box 82 of wood or other non-metallic material, which inner box is also 35 open at its top and is provided with vertical partition walls 83 arranged so as to separate the inner box into compartments corresponding to the number of the poles of the switch, said compartments being 40 shown as three in number and marked 84, 85, 86 in Fig. 5, which are in communication with one another through vertical slots 87 in the partition walls 83, in which slots move the carrier 16 common to the movable 45 members of the switch.

Provision is made for securing the oil well to the supporting frame in a manner as will enable this to be done by a single operator from one end of the said frame, 50 so that the danger of shocks and the serious effects often resulting therefrom are avoided or at least reduced to a minimum, and so that the switches may be set close together side by side and thus economize in room. 55 For this purpose I employ sliding bolts or bars 90 (see Figs. 4, 5, 6 and 7), which extend through suitable slots in the end walls of the metal box 80 near the top thereof, and are provided with fingers 92, which 60 pass above and rest upon fingers or lugs 93 depending from the supporting frame 26. The fingers 92 and lugs 93 are so located with relation to each other, that the bolts or bars 90 project through both end walls 65 before the said fingers are engaged with

said lugs, thus insuring the oil well being firmly supported by the bolts when the fingers are engaged with the said lugs.

The locking bolts or bars 90 may and preferably will be connected at one end by a cross or tie bar 94 having a depending lip 95 (see Fig. 5), which constitutes a handle, and the tie bar 94 has co-operating with it a removable pin 97, which is inserted down through a hole in a lug 98 on the end 70 of the supporting frame 26, and constitutes a lock for the sliding bolts or bars 90 and prevents accidental disengagement of the said bolts or bars from the lugs 93. The pin 97 may be attached to the frame 26 by a 75 chain 99 as represented in Fig. 2. It will thus be seen, that the oil well may be quickly and easily detached from the frame, and again attached thereto, for it is only necessary for the operator to place one hand 80 under the oil well to support the same, remove the pin 97 and withdraw the locking bolts 90 until they are disengaged from their supporting lugs 93, after which the hand supporting the well is lowered until its top 90 clears the switch contact members; and to replace the same the reverse operations are performed. Additional locking means for the sliding bars or bolts 90 may be provided, in the form of pins 100, (see Fig. 4), which 95 extend through suitable holes in the free end of the said bars and are adapted to engage the end of the box if it should be attempted to entirely withdraw the said bolts or bars, and said pins also serve as stops 100 for the bolts or bars in their withdrawal movement, and are so arranged as to engage the box or well when the fingers are disengaged from the lugs 93. The downward movement of the carrier 16 and its attached 105 movable contact members may be cushioned by a washer 101 of rubber or other yielding material (see Fig. 5), which rests on the frame 26 and is engaged by the flange 57 on the rod 53.

Claims.

1. In an electric circuit controller, in combination, a supporting frame, a stationary contact member located below said frame, a conducting rod extended through said frame 115 and to which said stationary contact member is secured, a sleeve of insulating material surrounding said rod below said frame and provided at its upper end with an enlarged socket and at its lower end with a 120 depending flange opposite to said stationary contact member, a second sleeve of insulating material located above said frame and having its lower portion extended through the said frame and into the socket in the 125 first mentioned sleeve, and provided at its upper end with a socket, means co-operating with said conducting rod to clamp said sleeves in fixed relation to each other, a removable terminal secured to the upper end 130

of said rod, and a sleeve of insulating material surrounding said removable terminal and movable longitudinally thereof, and provided with a reduced portion extended 5 into the socket of the second-mentioned sleeve and a movable contact member co-operating with said stationary contact member, substantially as described.

2. In an electric circuit controller, in combination, a supporting frame, a conducting rod extended through said frame, means to insulate said rod from said frame, a detachable terminal having a split socket in its lower end extended but partially the length 15 of the terminal and into which the upper end of said rod is extended and provided with a separate socket in its upper end for the reception of an electric conductor, said upper socket being separated from the lower 20 socket by a transverse wall and having a continuous circumferential wall, means to clamp the split socket onto said rod, a stationary contact member secured to the lower end of said rod, and a movable contact member 25 operating with said stationary contact member, substantially as described.

3. In an electric circuit controller, in combination, a substantially horizontal supporting frame, a plurality of pairs of stationary 30 contact members located below said frame and spaced apart, a substantially heavy slab of insulating material movable vertically between the contact members of each pair and interposed between the same in the closed 35 position of the circuit controller, a plurality of movable contact members secured to the lower portion of said slab and extended transversely thereof to co-operate with the pairs of stationary contact members, and 40 means to raise said slab toward the supporting frame to engage the movable contact members with the pairs of stationary contact members.

4. In an electric circuit controller, in combination, a plurality of pairs of stationary contact members spaced apart, a substantially heavy slab of insulating material vertically movable between the contact members of said pairs and provided on its upper 45 edge with a downwardly extended hole and below its upper edge with a transverse hole intersecting said vertical hole, a nut inserted into said transverse hole, a threaded rod extended down through said vertical 50 hole and engaging said nut, means connected with said rod for moving said slab upwardly between the contact members of each pair of stationary contact members, and a plurality of contact members secured 55 to said slab at its lower end and extended on opposite sides thereof to engage the stationary contact members in the elevated position of said slab.

5. In an electric circuit controller, in combination, a substantially horizontal sup-

porting frame, a plurality of pairs of stationary contact members located below and supported by said frame with the members of each pair separated from each other, walls of insulating material interposed between the adjacent members of said pairs, a plurality of movable contact members co-operating with said stationary contact members, a slab of insulating material interposed between the members of each pair of stationary members and movable vertically between the members of said pairs and between the insulating walls separating the members of adjacent pairs, and to which the movable contact members are secured, 70 and means to raise said slab, substantially as described.

6. In an electric circuit controller, in combination, a vertically arranged slab or plate, a plurality of movable contact members secured to the lower part of said slab or plate to extend transversely thereof below the same, and stationary contact members located on opposite sides of said plate or slab and with which said movable contact members co-operate, substantially as described.

7. In an electric circuit controller, in combination, a substantially horizontal supporting frame provided with depending lugs near its opposite sides, a receptacle or well 80 for oil, and sliding bolts or bars extended through said well near its upper end and provided with fingers which co-operate with said lugs to secure said well to said frame, substantially as described.

8. In an electric circuit controller, in combination, a substantially horizontal supporting frame provided with depending lugs near its opposite sides, a receptacle or well 85 for oil, sliding bolts or bars extended through said well near its upper end and provided with fingers which co-operate with said lugs to secure said well to said frame, a cross bar joining said sliding bolts or bars, 90 and a locking pin extended through said frame and co-operating with said cross bar, substantially as described.

9. In an electric circuit controller, in combination, a substantially horizontal supporting frame, an oil well or receptacle, and 105 means carried by said well or receptacle and movable across the same and co-operating with said supporting frame for securing the said well or receptacle thereto, substantially as described.

10. In an electric circuit, in combination, a substantially horizontal supporting frame, an oil well or receptacle located below said frame and bodily movable in a vertical plane toward and from the same, and means extended from the front of the oil well transversely thereof and substantially parallel with said frame and co-operating with the latter to secure the oil well to the said frame by moving said means from the front of the 115 frame.

oil well transversely of the latter in one direction and to release the oil well by movement of said means from the front of the oil well in the opposite direction, substantially as described.

5. 11. In an electric circuit controller, in combination, a substantially horizontal supporting frame, an oil well or receptacle depending therefrom and supported thereby, 10 a vertically arranged partition in said well having a vertically arranged slot open at its upper end, a vertically arranged slab or plate extended down into and through said slot and movable therein, a plurality of 15 movable contact members secured to the

lower part of said slab or plate below and in line with the same to move bodily therewith and extended transversely thereof, and stationary contact members located on opposite sides of said plate or slab and toward 20 and from which the opposite ends of said movable contact members are moved, substantially as described.

In testimony whereof, I have signed my name to this specification in the presence of 25 two subscribing witnesses.

JOHAN M. ANDERSEN.
